UNITED STATES PATENT OFFICE

WILLIAM G. MUELLER, OF DENVER, COLORADO, ASSIGNOR TO GARDNER-DENVER COMPANY, OF DENVER, COLORADO, A CORPORATION OF DELAWARE

CHUCK STRUCTURE

Application filed February 17, 1928. Serial No. 255,106.

In one form of chuck structure the tool-engaging or socket member of the chuck is screwed into the rotating sleeve, by which rotary motion is transmitted to the socket member and therefore to the tool engaged therein. The socket member is subject to considerable wear, which makes it expedient that it be removable for replacement. In actual use it has been found a very difficult matter 5 to remove said member from the sleeve after the drill has been in operation for some time, due to the binding of the screw threads. As a consequence upon rotating the socket member in an endeavor to remove it from the 10 sleeve, the sleeve usually rotates with the chuck.

One of the objects of the present invention is to provide means of a simple nature whereby the sleeve can be locked against rotation. As a consequence it is positively held so that the socket or tool-engaging member can be turned and consequently unscrewed from said sleeve.

In the accompanying drawings: 25 Figure 1 is a side elevation of the chuck end of a tool with the sleeve locking means in place thereon,

Figure 2 is a longitudinal sectional view therethrough,

30 Figure 3 is a cross sectional view on the line 3—3 of Figure 1, and with the locking device in its inoperative position,

Figure 4 is a view similar to Figure 3, but showing the sleeve locked by said device,

35 Figure 5 is an end view of the locking device and its mounting when in the position shown in Figure 3,

Figure 6 is a similar view, but with the 40 locking device in the position shown in Figure 4,

Figure 7 is a perspective view of the locking device.

In the structure disclosed, a housing 8 is 45 employed, within which is the usual rotary sleeve 9, and said sleeve is usually provided on opposite sides with flattened portions 10 for the reception of a holding wrench or for engagement by the jaws of a vise or other 50 tool when said sleeve is not in place in the

housing. The front end of the sleeve is internally threaded, as shown at 11. A tool-engaging or socket member 12 fits within the sleeve 10 and has external threads 13 that screw into the threads 11 of said sleeve. This member 12 projects beyond the front end of the housing and has an enlargement 14 in the form of a hood that overhangs the front end of the sleeve 10 and the front end of the housing 8. The member 12 is provided with a socket 15 that receives the shank 16 of the steel or other tool. So far as thus described, the structure is well known.

In the present embodiment the housing 8 is modified to the extent of having a transverse enlargement 17 provided with a bore 18 that intersects the bore of the housing and in this bore 18 is rotatably mounted a transversely disposed locking bolt 19. The bolt, as shown in Figures 3, 4 and 7, has one side 70 cut-away to provide a recess or socket 20, and obviously by rotating the bolt the recess may be brought to a position as shown in Figure 3, so that the sleeve will enter it and be freely rotatable. If, however, one of the flat sides 10 of the sleeve is brought alongside the bolt and the bolt is turned, as shown in Figure 4, then said bolt will enter the seat 10 and prevent the rotation of said sleeve.

The bolt 19 is preferably provided at one 75 end with a head 21, behind which is a coiled spring 22 seated in a socket 23 formed in the adjacent end of the enlargement 17 and bearing against the inner end wall thereof. The bolt therefore is permitted a longitudinal 80 movement against the tension of the spring 22. The other end of the enlargement is provided with a notch 24, and a stud 25 projecting from one side of the adjacent end of the bolt is adapted to engage in the notch, as 85 shown in Figure 3, or to ride out of said notch and along the end face of the enlargement 17. The stud 25 is preferably the reduced projecting end of a head 26 fitted in a socket 27 90 formed in the end of the bolt 19, and said head 26, as will be clear by reference to Figure 4, has a portion located in the bore 18 of the enlargement 17, so that it will be retained in the socket 27.

Under normal operating conditions the 100

bolt is in the position shown in Figure 3, in which case the stud 25 is in the notch 24, and the cut-away seat 20 is facing the rotary sleeve 9, so that said sleeve can rotate within the housing 8. When it becomes desirable to detach the socket member 12 the sleeve 9 is rotated until one of the flat seats 10 is alongside the bolt, said bolt is then given a longitudinal movement to disengage the stud 25 from the socket 24, and the bolt is turned until its body extends across said seat 10. The sleeve is now locked, whereupon if a tool is applied to the socket member 12, obviously it can be unscrewed from the sleeve.

15. From the foregoing, it is thought that the construction, operation and many advantages of the herein described invention will be apparent to those skilled in the art, without further description and it will be understood 20 that various changes in the size, shape, proportion and minor details of construction may be resorted to without departing from the spirit or sacrificing any of the advantages of the invention.

25. What I claim, is:

1. In a drilling tool, the combination with a housing, of a driving sleeve rotatably mounted in the housing, a tool-receiving wear member detachably fitted to the sleeve and 30 normally rotated therewith to rotate a tool detachably engaged therein, and means for temporarily securing the sleeve against rotation in the housing to permit the tool-receiving member being moved with respect to 35 the sleeve to detach said member.
2. In a drilling tool, the combination with a housing, of a driving sleeve rotatably mounted in the housing, a tool-receiving wear bushing screwed into the outer end of the 40 sleeve and having a longitudinal open ended socket for the reception of the tool, and a holding bolt carried by one side of the housing and adapted to engage with one side of the sleeve for temporarily holding the sleeve 45 against its normal rotative motion in the housing to permit the detachment of the bushing.
3. In a drilling tool, the combination with a housing, of a driving sleeve rotatably 50 mounted in the housing and having opposite flat faces for engagement by holding jaws, a tool-receiving bushing screwed into the outer end of the sleeve and having a longitudinal open ended socket for the reception of 55 the tool, and a holding bolt rotatably mounted in one side of the housing and having a portion that is adapted to bear against one of the flat faces of the same for temporarily holding the sleeve against its normal rotative motion in the housing to permit the detachment of the bushing.

In testimony whereof, I affix my signature.

WILLIAM G. MUELLER.
